US0D1071353S

(12) **United States Design Patent** (10) Patent No.: **US D1,071,353 S**
(45) Date of Patent: ** Apr. 15, 2025

(54) **HELMET**

- (71) Applicant: **VOG—IMAGE POLICE INC.**,
Taichung (TW)
- (72) Inventor: **Gavin Michael Vos**, Taichung (TW)
- (73) Assignee: **VOG—IMAGE POLICE INC.**,
Taichung (TW)

(**) Term: **15 Years**

(21) Appl. No.: **29/862,983**

(22) Filed: **Dec. 14, 2022**

(51) LOC (15) Cl. **02-03**

(52) U.S. Cl.

USPC **D29/102**
